JETTY CONSTRUCTION

Application filed October 1, 1930. Serial No. 435,615.

It is the object of my invention to produce a current-retard, or a device suitable for use in controlling the deposition of sand-bars in streams or for protecting the banks of streams 5 against the eroding action of the water which flows in contact with them. More specifically, it is my object to produce a current-retard of a flexible nature which is adapted for use in a variety of situations. A further object of my 10 invention is to produce a current-retard of a simple and economical construction which will prove durable and effective in use.

In carrying out my invention, I build my current-retard of a number of units, each of 15 which comprises an open-wound helical coil of steel or iron wire or similar material. The current-retard may embody a single one of such coils, but preferably embodies a plurality of coils arranged in parallel relation and secured together. The turns of one of the coils may be spaced and held in properly spaced relation by securing the coil at intervals to a longitudinally extending element which may take the form of a cable by which the complete 20 current-retard is anchored in place. The action of the open-wound coils in retarding the velocity of the stream-flow to cause the deposition of sediment may be assisted by one or more screens or other means adapted to 25 intercept drift small enough to pass between the turns of the current-retard coils.

The accompanying drawing illustrates my invention: Fig. 1 shows a current-retard embodying my invention used as a mattress to 30 protect a caving stream-bank; Fig. 2 is a fragmental plan of the current-retard; Fig. 3 is a perspective view illustrating the manner in which the individual coils of the retard are 35 formed; Fig. 4 is a view similar to Fig. 2, but showing a slightly modified arrangement; Fig. 5 is an end elevation of the retard; and Fig. 6 is a perspective view showing the retard as used to create sand-bars in the stream.

40 As previously stated, my current-retard is formed of one or more open-wound helical coils 10 of wire or similar material. Associated with one of such coils, I provide a longitudinally extending element 11 which is 45 conveniently in the form of a wire cable. At

intervals, the coil 10 is secured to the cable 11 as by means of wire ties 12.

If the retard is to embody more than one coil, as it usually does, the other coils are disposed parallel to the first coil, preferably in 55 overlapping relation as indicated in Fig. 5, with the turns of each coil extending into the spaces between the turns of the adjacent coils. The coils are secured together, conveniently by means of wire ties 13 at points where the 60 coil-turns of the individual coils cross. Generally, it will not be necessary to use more than one of the cables 11, but additional cables can be used if desired.

The individual coils from which the retard is constructed may be formed as indicated in Fig. 3. Wire of the type adapted for use in my current-retard is usually marketed in the form of a closely wound coil 15. The wire can be drawn off from this coil axially 65 as indicated in Fig. 3 to form the open-wound coil of the retard. As it is drawn off from the supply-coil 15, the wire may be secured at intervals to the cable 11 in order to space 70 the turns properly.

The helical coils of which the current-retard is composed may all be of the same hand, as indicated in Fig. 2; or adjacent coils may be of opposite hand, as indicated in Fig. 4. I prefer the latter construction, as I believe 75 it results in a current-retard of greater strength.

The retard built up as above described may be used in a variety of situations. In Fig. 1, I have shown a retard as used to protect the 80 caving bank of a stream. Here, the number of individual open-wound coils is sufficient to create a mattress extending desirably from or above the high-water mark to a point below the surface of the stream. The retard is shown as held in place by transversely extending cables 16 secured to stakes 17 on the bank or stream-bed.

In Fig. 6, the retard is shown as extending 85 transversely into the stream from a bank thereof in order to retard the current adjacent such bank and form a bar on the downstream side of the retard. When the retard is to be so used, the cable 11 may extend 90 beyond the ends of the retard and may be se- 100

cured to anchoring stakes 17 to hold the retard in place.

Drift carried downstream by the current is intercepted by the retard with the result that the velocity of stream-flow in the vicinity of the retard is decreased and sediment is deposited. To facilitate the deposition of sediment behind the retard, the coils 10 may be supplemented with a screen 20 which, as shown in Figs. 2 and 5, extends longitudinally of the retard and is supported against the inside of one of the coils 10. This screen 20 is shown in the drawing as a wire-mesh screen, but brush or other means may be used to accomplish the same object. The purpose of the screen 20 is to catch small drift which might otherwise pass through the retard. Such drift collected on the screen serves further to retard the velocity of stream-flow and thus to aid in the deposition of sediment adjacent the retard.

It will be apparent that a current-retard embodying the invention above set forth will be adaptable for use in a variety of situations. It can be used alone or in association with jetties of heavier construction. In addition, because of its flexible character, it is adapted to follow the contours of the bank or stream-bed, thus increasing its effectiveness.

I claim as my invention:

1. A current-retard, comprising a plurality of open-wound self-supporting helices disposed generally parallel to each other, the turns of each helix overlapping but not interlinking respectively the turns of adjacent helices, and means for securing said helices together.

2. A current-retard, comprising an open-wound self-supporting helix of wire or the like, successive turns of the helix being spaced apart a distance at least several times as great as the axial thickness of the wire or the like of which the helix is formed.

3. A current-retard, comprising an open-wound self-supporting helix of wire or the like and a member extending longitudinally of said helix and secured to turns thereof to space such turns, successive turns of the helix being spaced apart a distance at least several times as great as the axial thickness of the wire or the like of which the helix is formed.

4. A current-retard as set forth in claim 3 with the addition that said longitudinally extending element is a cable, said cable extending beyond the ends of said helix for attachment to anchoring means.

5. A current-retard, comprising an open-wound helix of wire or the like, and drift-catching means extending between adjacent turns of said helix, successive turns of the helix being spaced apart a distance at least several times as great as the axial thickness of the wire or the like of which the helix is formed.

6. A current-retard, comprising a plurality of open-wound helices disposed generally parallel to each other, the turns of each helix overlapping but not interlinking respectively the turns of adjacent helices, means for securing said helices together, and a member extending longitudinally of one of said helices and secured to turns thereof to space such turns.

7. A current-retard, comprising a plurality of open-wound helices disposed generally parallel to each other, the turns of each helix overlapping but not interlinking respectively the turns of adjacent helices, means for securing said helices together, a cable extending longitudinally of one of said helices and secured to turns thereof to space such turns, and anchoring means to which said cable is attached to aid in holding the retard in place.

8. The process of making a current-retard, comprising drawing wire axially from a close-wound coil of wire to form an open-wound helix, and securing turns of said helix to spacing means.

9. A current-retard, comprising an open-wound helix of wire or the like, and a drift-catching screen supported from said helix and extending between adjacent turns thereof.

In witness whereof, I have hereunto set my hand at Topeka, Kansas, this 4th day of September, A. D. one thousand nine hundred and thirty.
